UNITED STATES PATENT OFFICE.

JOHN S. PURDY, OF BROOKLYN, NEW YORK.

FOUNTAIN-PEN.

SPECIFICATION forming part of Letters Patent No. 279,104, dated June 5, 1883.

Application filed March 29, 1883. (Model.)

To all whom it may concern:

Be it known that I, JOHN S. PURDY, of Brooklyn, county of Kings, and State of New York, have invented a new and useful Improvement in Fountain-Pens, of which the following is a full, clear, and exact description, reference being had to the accompanying drawings, making part of this specification.

The invention relates to that class of pens which are provided with a hollow holder or ink-reservoir, from which the ink is automatically caused to flow to the pen during the operation of writing.

The invention consists in the combination, with the pen and holder, of a double feed-tube having two ducts—one above and the other below the pen—an adjustable valve, wire in the ducts of the feed-tube, and a moving tongue, each of which features acts separately, as well as in combination with the others, to cause the ink to flow more freely and regularly while writing with the pen, and also to prevent the clogging of the flow of the ink by the accumulation of air bubbles or other obstructions.

Figure 1 is a vertical longitudinal and sectional view, on an enlarged scale, of a fountain-pen embracing my invention. Fig. 2 is an enlarged sectional view of the valve. Fig. 3 is a perspective view of the valve with its oscillating tongue and wire conductors; and Fig. 4 represents a transverse section through the valve-chamber and valve-stem below the valve, and looking toward the reservoir.

In the fountain-pens in use employing a tubular reservoir-holder, so far as they have come to my knowledge, air-tubes have been employed communicating with the upper end of the holder, which is provided ordinarily with a movable cap made adjustable for admitting air when the pen is in use, and for closing said air-tubes and preventing the escape or evaporation of the ink when the pen is not in use. In my construction this air-duct communicating with the upper end of the holder is dispensed with, and the holder is closed or made air-tight at said end, the air necessary to supply the place of the ink flowing out when the pen is in use being obtained through a duct directly above the pen itself, the ink passing outward to the pen through a separate duct underneath the pen, as herein-after explained.

In the accompanying drawings, A represents a tubular holder forming the ink-reservoir, said holder being shown provided at its upper end with a close-fitting screw-plug, A', which, being made removable, facilitates the cleaning of the holder, but when in place is air-tight and prevents the admission of air or the escape of ink at said end. The lower end of the holder A is provided with an internal screw-thread, which matches a screw-threaded shank on the upper end of the feed-tube B. This feed-tube is made in two parts, b and b', to permit the introduction of a valve, C, within a chamber, C', formed in the larger lower end of the part b. The chambered portion b is provided with an internal screw-thread, and at its extreme end is made with a flaring annular mouth matching a tapering annular flange or rib, b², on the part b', and which, inside of or above said rib or flange, has an external screw-thread matching the screw-thread in the chambered end of the part b. By this construction, as the part b' is screwed into the part b, the tapering annular collar is drawn or forced, wedge like, into the flaring end of the part b until a perfectly-tight joint between the two parts of the feed-tube is secured. The part b' of the feed-tube has a central partition, b³, dividing the longitudinal perforation through it into two parts or ducts, d and d', one above and the other below the slit e for the pen. This slit e is curved from side to side to conform to the arching shape of and adapting it to receive a pen of ordinary form, the slit e, in connection with a covering-sleeve, D, screwing over the part b' and against the vertical outer face of the flange b², and the end of the part b serving to hold said pen. The ducts d and d', at their inner ends, both communicate with the valve-chamber C', and extend thence, one, d, over the pen E and slit e, forming the air-duct for the admission of air to the holder, and the other, d', underneath said pen and slit, forming the ink-duct, through which the ink flows outward to the pen E.

The valve C is made in two parts, c and c'. One, c, has a screw-threaded longitudinal perforation or socket, and the other, c', has a screw-threaded shank, c², fitting and adjustable in said socket, and they have on their adjacent ends each a cross-head or radial ears, f and f', which, by the adjustment of the parts c and c', may be set nearer to each other or far-

ther apart, or at any desired angle or relation one with the other for regulating the flow or passage of the ink. The upper end of the part *c* of the valve or valve-stem is socketed and receives the lower end of a tongue, *g*, which is connected therewith by a pin or pivot, *h*, passing through an eye in the end of said tongue, leaving the upper end of the tongue, which extends up within the tubular holder, free to swing or oscillate from side to side to conform to the movements of the pen. The shank *c* of the part *c* is perforated or grooved, and has a small wire, *i*, connected with it, the ends or arms of which pass, one, *i'*, through or partly through the air-duct *d*, and the other, *i''*, similarly arranged relatively to the ink-duct *d'*.

The upper tongue of the slit end of the feed-tube *B* is by preference made somewhat lighter than the lower tongue, to adapt it to yield slightly to the pressure of the pen upon it when in use, and it is also preferably made a little shorter, such construction serving to make the air-duct a little shorter, and to place the mouth of said duct a little higher than the mouth or outer end of the lower or ink duct when the pen is in use.

In operation the adjustment of the parts of the valve serves to regulate the flow of the ink through the valve-chamber, as explained, and the wires connected therewith serve to prevent the formation of air bubbles, and also to break any bubbles that may in any way have been formed in other parts of the pen, and thereby to insure an even and steady flow of the ink, while the tongue *g*, pivoted at its lower end within the feed-tube, with its swinging end extending up into the reservoir-holder, serves, by its oscillation or movements from side to side with the movements of the pen in use, to break any bubbles of air passing from the air-duct up to the upper end of the holder to supply the place of the escaping ink. The "valve," so called, is not designed to close the tube or ink and air ducts entirely, but only to obstruct more or less, by its adjustment, as described, the flow of the ink to the pen, and its cross-heads will be adjusted to the desired relation to each other for that purpose when the pen is opened for filling the reservoir, their adjustment being governed by the nature of the ink employed, some inks flowing much more freely than others. While the ink may descend to the pen by both the upper and lower ducts,

owing to its superior gravity, it will naturally tend to the lower duct, while the air will as 55 naturally tend to and will enter the valve-chamber through the upper duct.

*A*² represents a removable cap or cover for covering and protecting the pen when not in use. 60

What I claim as my invention is—

1. A feed-tube made in two or more parts, the lower one having two ducts between the ink-reservoir and the pen—one above and the other below the pen—which, in combination, carry 65 the ink out to supply the pen and the air in to take the place of the ink, substantially as described.

2. The combination, with the feed-tube of a fountain-pen, of a valve provided with two 70 cross-heads made adjustable, one relatively to the other, for adjusting their angle of relation and distance apart, substantially as and for the purpose described.

3. In a fountain-pen, a valve made in two 75 or more parts adjustable relatively to each other, each provided with a cross-head, which, by the adjustment of the parts of the valve, may be set at any desired angle of relation one to the other and at any desired distance apart, 80 in combination with an oscillating tongue, substantially as described.

4. An oscillating tongue connected with the valve in the feed-tube by a hinge-joint, and extending up into the reservoir-holder and 85 forming an agitator within the body of the feed-tube, substantially as described.

5. An ink-conductor made of wires connected with the valve and running down through ducts leading to the pen, substantially 90 as described.

6. A feed-tube provided with a slit for the pen, and two ink-ducts, one above and the other below the slit, in combination with the covering-sleeve for holding the pen, substantially as 95 described.

7. The combination, with a reservoir-holder, of the feed-tube, valve, moving tongue or agitator, and wire conductor, substantially as described. 100

In testimony whereof I have hereunto set my hand.

JOHN S. PURDY.

Witnesses:

H. B. ZEVELY,
EDW. W. DE KNIGHT.

It is hereby certified that in Letters Patent No. 279,104, granted June 5, 1883, upon the application of John S. Purdy, of Brooklyn, New York, for an improvement in "Fountain Pens," an error appears as follows: The date of filing the application complete is printed "March 29, 1883," whereas it should be "January 18, 1883;" and that the proper correction has been made in the files of the case in the Patent Office, and should be read in the said Letters Patent to make the same conform therewith.

Signed, countersigned, and sealed this 19th day of June, A. D. 1883.
